SMOOTH FACE ELASTIC FABRIC

Filed March 15, 1929

UNITED STATES PATENT OFFICE.

LESTER B. CHISHOLM, OF WATERBURY, CONNECTICUT, ASSIGNOR TO AMERICAN MILLS CO., OF WATERBURY, CONNECTICUT, A CORPORATION.

SMOOTH-FACE ELASTIC FABRIC.

Application filed March 15, 1929. Serial No. 347,323.

This invention relates to an improvement in elastic fabrics and particularly to elastic fabrics designed for use in corsets, girdles, brassières, and other articles of personal 5 wear.

The object of this invention is to provide a durable and attractive elastic fabric constructed with particular reference to having one or more smooth unribbed faces which 10 may be placed adjacent to or in contact with the skin without appreciably marking or irritating the same.

Another object of this invention is to provide an elastic fabric having its inner face 15 smooth and its outer face provided with an attractive design.

With the above and other objects in view, my invention consists in a smooth-face elastic fabric characterized by having a series of 20 parallel elastic warp-strands of relatively large diameter spaced apart to form gaps therebetween; a group of lesser-diameter textile warp-threads interposed in the gaps between the said elastic warp-strands; a plurality of filler-threads spanning certain of the gaps between the said elastic warp-strands and also spanning the textile warp-threads therein and interwoven with the textile warp-threads in certain of the other 25 gaps between the said elastic warp-strands; and a plurality of filler-threads spanning the gaps in which the first-mentioned filler-threads are interwoven and interweaving with the textile warp-threads in the gaps 30 which are spanned by the first-mentioned filler-threads; whereby the gaps between the ridges formed by the large-diameter elastic warp-strands are spanned by filler-threads to produce a continuous relatively-smooth non- 35 irritating face.

My invention further consists in a smooth-face elastic fabric characterized as above and having certain other features as will be hereinafter described and particularly recited in 40 the claims.

In the accompanying drawings:

Fig. 1 is a broken view of the inner smooth face thereof;

Fig. 2 is a similar view of the outer face 50 of an elastic fabric embodying my invention;

Fig. 3 is a broken enlarged-scale schematic transverse sectional view taken parallel with the filler-threads; and

Fig. 4 is an enlarged-scale schematic 55 broken face view looking toward the smooth

inner face of the fabric; the threads being spaced apart for purpose of clarity.

It is characteristic of elastic fabrics that the rubber warp-strands therein are of greater diameter than the cotton or silk warp-threads, so that when the filling-threads are interwoven with both the elastic warp-strands and the smaller intermediate warp-strands, a series of longitudinal ribs or ridges stand out from the face of the fabric, due to 60 the greater diameter of the elastic warp-threads, so that such a fabric is uncomfortable to the wearer, since the aforesaid ribs 65 will both mark and irritate the skin.

In the form of elastic fabric herein chosen 70 for the illustration of my invention, I employ a series of parallel elastic warp-strands 10 of relatively large size in cross-section and spaced apart to accommodate between them three (more or less) textile warp-threads 11. 75

The filler-threads or picks running cross-wise of the above mentioned warp-strands and warp-threads are interwoven with the latter in repeating cycles of four phases or picks each. 80

A filler-thread 12 (Fig. 3) overlies and extends between alternate pairs of elastic warp-strands 10 as at 13 on the back face of the fabric and also overlies the three (more or less) textile warp-threads between the respective strands of the said alternate pairs of elastic warp-strands. 85

After passing over alternate pairs of elastic warp-strands and the warp-threads included between the respective strands of each 90 of the said alternate pairs, the said filler-thread 12 is interwoven as at 14 with the textile warp-threads 11 in the spaces between the said alternate pairs of elastic warp-strands 10, as clearly shown in Fig. 3 of the 95 drawings.

The second filler-thread or pick 15 beyond the filler-thread 12 just above described, reaches around the front sides of the elastic warp-strands 10 as at 16, and 100 interweaves with the warp-threads 11 between the said strands 10, as at 17. This regular interweaving of the filler-thread 15 with the elastic warp-strands and the textile warp-threads continues until such time 105 as it is desired to have the said filler-thread 15 emerge upon the front face of the fabric to produce the design effect shown in Fig. 2 of the drawings. At this point the said filler-thread 15 then overlies, as at 18, on 110

the front face of the fabric, alternate pairs of elastic warp-strands 10, together with the warp-threads 11 between the respective strands thereof, as shown in the center portion 5 of Fig. 3. Between the alternate pairs of warp-strands 10 which the said filler-thread 12 overlies, the same is interwoven with the textile warp-threads as at 19.

The third filler-thread or pick 20, complementing the filler-thread 12, overlies as 10 at 21, on the back face of the fabric, the spaces between the pairs of elastic warp-strands 10 which are not overlain by the said filler-thread 12. In the spaces between 15 the pairs of elastic warp-strands which are overlain by the filler-thread 12 the filler-thread 20 is interwoven with the textile warp-threads 11.

A fourth filler-thread or pick 22, complementing the filler-thread 15, reaches 20 around the front sides of the elastic warp-strands 10 and interweaves with the warp-threads 11 between the said strands in the same manner that the filler-thread 15 before 25 referred to is interwoven. This regular interweaving of the filler-thread 22 with the elastic warp-strands 10 and the textile warp-threads 11 continues until such time as it is desired to have the said filler-thread 22 30 emerge upon the front face of the fabric to complement the filler-thread 15 in producing the design effect shown in Fig. 2 of the drawings. At this point the said filler-thread 22 then overlies as at 23, on the front 35 face of the fabric, the space between the elastic warp-strands 10 which are not overlain by the reaches 18 of the filler-thread 15. In the spaces between the said warp-strands which the said filler-thread 15 does overlie, 40 the said filler-thread 22 is interwoven with the textile warp-threads 11, all as clearly shown in Fig. 3 of the drawings.

Another cycle of weaving now takes 45 place starting with the filler-thread 12 and so on indefinitely.

By reference to Fig. 2 of the drawings, which shows the front face of the fabric bearing a block design, it will be noted that there is a space between the groups of 50 designs in which the design-producing filler-threads 15 and 22 are not required to appear upon the front face of the fabric to produce a design effect. In these spaces the said filler-threads 15 and 22 are merely interwoven in any approved manner to provide 55 a background for the designs.

It will be obvious that the number of textile warp-threads 11 between the elastic warp-strands 10 may be varied in number 60 and also that the weaving cycles may consist of more or less than four phases or picks each.

I claim:

1. As a new article of manufacture, a 65 smooth-face elastic fabric comprising a

series of parallel spaced-apart elastic warp-strands of relatively-large diameter; a group of lesser-diameter textile warp-threads interposed between the said elastic warp-strands; a plurality of filler-threads 70 overlying a group of two or more of the said elastic warp-strands, together with textile warp-threads therebetween and interwoven with the textile warp-threads on either side of the said group of elastic warp-strands; 75 and a plurality of filler-threads overlying the groups of textile warp-threads with which the first-mentioned filler-threads are interwoven and also overlying the elastic warp-threads flanking the same and interwoven with the textile warp-threads spanned by the first-mentioned filler-threads; whereby the gaps between the ridges formed by the large diameter elastic warp-strands are spanned by filler-threads to produce a continuous 80 relatively-smooth non-irritating face.

2. A smooth-face elastic fabric as defined in claim 1 and having additional filler-threads 90 normally interwoven with the elastic warp-strands and textile warp-threads and periodically emerging upon the face of the fabric opposite its smooth face and overlying groups of two or more elastic warp-strands, 95 together with the textile warp-threads between the respective strands thereof to produce a design effect.

3. A smooth-face elastic fabric as defined in claim 1 and having alternate filler-threads 100 or picks respectively exposed upon the back and front faces of the fabric to respectively produce the smooth surface on the back face and a design effect upon the front face.

4. As a new article of manufacture, a smooth-face elastic fabric comprising a series of parallel spaced-apart elastic warp-strands of relatively-large diameter; a group of lesser-diameter textile warp-threads interposed between the said elastic warp-strands; a plurality of filler-threads spanning alternate 105 spaces between the said elastic warp-strands together with the textile warp-threads in such alternate spaces and interwoven with the textile warp-threads in the spaces intermediate the said alternate spaces; 110 and a plurality of filler-threads overlying the groups of textile warp-threads with which the first-mentioned filler-threads are interwoven and also overlying the elastic warp-threads flanking the latter and interwoven with the 115 textile warp-threads spanned by the first-mentioned filler-threads; whereby the gaps between the ridges formed by the large-diameter elastic warp-threads are spanned by filler-threads to produce a continuous relatively-smooth non-irritating face.

5. A smooth-face elastic fabric as defined in claim 4 and having additional filler-threads normally interwoven with the elastic warp-strands and textile warp-threads and 120

periodically emerging upon the face of the fabric opposite its smooth face and overlying alternate spaces between the elastic warp-strands, together with the textile warp-
5 threads therebetween to produce a design effect.

6. A smooth-face elastic fabric as defined in claim 4 and having alternate filler-threads or picks respectively exposed upon the back and
10 front faces of the fabric to respectively produce a smooth surface on the back face and a design effect upon the front face.

7. As a new article of manufacture, a smooth-face elastic fabric comprising a series
15 of parallel elastic warp-strands of relatively-large diameter spaced apart to form gaps therebetween; a group of lesser-diameter textile warp-threads interposed in the gaps between the said elastic warp-strands; a plu-

rality of filler-threads spanning certain of the gaps between the said elastic warp-strands and also spanning the textile warp-threads therein and interwoven with the textile warp-threads in certain of the other gaps between the said elastic warp-strands; and a plurality 20 of filler-threads spanning the gaps in which the first-mentioned filler-threads are interwoven and interweaving with the textile warp-threads in the gaps which are spanned by the first-mentioned filler-threads; whereby the 25 gaps between the ridges formed by the large-diameter elastic warp-strands are spanned by filler-threads to produce a continuous relatively-smooth non-irritating face.

In testimony whereof, I have signed this 35 specification.

LESTER B. CHISHOLM.
